UNITED STATES PATENT OFFICE.

WILLIAM C. HEATH, OF BELOIT, WISCONSIN, ASSIGNOR TO FAIRBANKS, MORSE & CO.,
OF CHICAGO, ILLINOIS, A CORPORATION OF ILLINOIS.

IGNITION SYSTEM FOR COMBUSTION ENGINES.

Application filed May 14, 1920. Serial No. 381,505.

To all whom it may concern:

Be it known that I, WILLIAM C. HEATH, a citizen of the United States, residing at Beloit, in the county of Rock and State of Wisconsin, have invented a certain new and useful Improvement in Ignition Systems for Combustion Engines, of which the following is a specification.

This invention relates to a firing mechanism for the cylinder of an internal combustion engine, particularly one in which the firing is done by a low tension oscillating magneto located at some little distance therefrom.

The object of the invention is to under these conditions connect the parts in such a manner that the firing is accurately and positively done at the proper time so as to obtain best operating results.

The invention consists in means for carrying out the foregoing objects which can be easily and cheaply made, which is compact and simple in construction, which works practically perfectly and is not liable to get out of order. More particularly the invention consists in features and details of construction hereafter more fully set forth in the specification and claim.

Referring to the drawings in which similar numerals represent the same parts throughout the several views,

Figure 1 is a plan view of mechanism illustrating this invention in its preferred form.

Figure 2 is a side view of the parts of Figure 1.

Figure 3 is an end detail view of the firing electrodes and attached parts removed from the engine cylinder.

Figures 1 and 2 show fragmentary portions 10 of the cylinder of a combustion engine perforated to receive a plug or head 12 detachably secured in place by any suitable means, as for instance a cover 40 having arms 15 fastened to the cylinder by screws 14. Extending thru this cylinder head or block 12 are two electrodes 16 and 18, the former stationary, and carried in insulated material 20, the latter rotatable and without insulation and therefore grounded. Electrode 16 carries a firing contact 22 detachably engaged by firing contact 24 on an arm 26 rotatable with and by member 18. Electrode 18 also carries a lever arm 28 pushed in one direction by a compression spring 30 socket-

ed at 32 in a suitable projection on the plug 12 outside the cylinder. The end of stationary electrode 16 which is outside the cylinder is screw threaded and provided with suitable nuts 34 and 36 to receive the end of the wire 38 leading to the magneto. The parts of the electrodes which are outside of the plug 12 and their attached parts are enclosed within a suitable case 40 detachably secured to the face of the plug 12 by screws 14, heretofore referred to. Case 40 is perforated at 42 to let the wire 38 go thru it and is also perforated at 44 to provide a sliding support for a reciprocatable push rod 46 leading to the magneto. The end 48 of this rod 46 which enters the case 40 engages the arm 28 and rocks it in a clockwise direction against the action of spring 30.

Rod 46 may be of any suitable length required to reach the magneto mechanism in its selected position adjacent to the engine cylinder. The end 50 of the rod 46 which is opposite to end 48 is reciprocatably mounted on a suitable portion, as for instance, a projecting lug 52 on the front frame plate 54 of the low tension magneto. This magneto is electrically of ordinary construction, comprising the magnets 56 and the rotatable armature 58, carried on shaft 60 whose front end is journaled in plate 54.

Front plate 54 is provided with forwardly projecting arms 62 and 64 located in the same horizontal plane on opposite sides of the center of shaft 60, said arms carrying projecting bolts or pins 66 to each of which is attached a retractile spring 68 in turn loosely connected in the usual manner to the adjacent one of a pair of integrally connected, oppositely disposed oscillating arms 70 detachably secured to the shaft 60 by means of a nut 72.

Depending from this member 70 is the usual operating arm 74 driven in the usual manner by the pin 76 carried on a rotating arm 78 propelled by the engine mechanism in the direction of the arrow 80.

Inside of arms 62 and 64 and behind the member 70 is a cam 82 detachably secured in place by the pressure of nut 72 acting thru member 70. Pivoted on a stud 84 projecting from plate 54 and adjacent this cam, is a depending rocker arm 86 held against the cam by a compression spring 88 bearing against and seated upon a lug 90 provided for it on the arm 62. The parts are so ar-

ranged and shaped that the rocking of arm 74 rocks cam 82 to swing the lever 86 between the dotted and full line positions of Figure 2, with the result that, as the lower end of lever 86 normally engages the end 50 of rod 46, the arm 86 then moving to the right, moves the rod and consequently the arm 28 against the action of spring 30.

The wire 38, heretofore referred to, is connected with magneto armature 58 at 90 in the usual manner.

The result of the construction described is that as arm 78 rotates the pin 76 strikes the arm 74 in its dotted line position and oscillates it to the left as viewed in Figure 2 until the pin 76 passes off from the end of the arm whereupon the springs 68 return the armature to original position. This oscillation of the armature generates the usual current which passes from the armature to the wire 38, to electrode 16, thence across the contacts 22 and 24 to electrode 18, and thence back thru the grounded parts of the device, viz, the metal of the device to the armature. This movement of the armature obviously oscillates cam 82, which in turn rocks arm 86 to move rod 46 to separate the contacts 22 and 24 at the proper time to cause the expected electric spark within the engine. By loosening the nut 72 the cam 82 and the arm 74 may be adjusted angularly with ref-

erence to each other to insure absolutely proper timing of the firing of the mixture in the engine cylinder.

By enclosing the electrode parts within 35 the case 40 the parts are protected from accidental injury and displacement in operation.

Having thus described my invention what I claim as new and desire to secure by Let- 40 ters Patent, is:—

In mechanism of the class described, a front frame of an oscillating magneto mechanism, arms extending forwardly from opposite sides of said frame, an armature shaft 45 extending thru said frame, oscillating mechanism for said shaft detachably secured thereto, a cam mounted on the shaft between the front plate and the oscillating mechanism and detachably adjustably held 50 in place by the oscillating mechanism, and means for firing an engine cylinder remote from the magneto said means being located in proximity to said cam and actuated thereby.

In witness whereof, I have hereunto subscribed my name in the presence of two witnesses.

WILLIAM C. HEATH.
